(57) **CLAIM**

The ornamental design for a sanitary pad, as shown and described.

DESCRIPTION

FIG. 1 is a front elevation view of a first embodiment of a sanitary pad showing the new design;

FIG. 2 is a rear elevation view thereof;

FIG. 3 is a right side view thereof, wherein the left side view is identical thereto;

FIG. 4 is a top view thereof, wherein the bottom view is identical thereto;

FIG. 5 is a front elevation view of a second embodiment of a sanitary pad showing the new design;

FIG. 6 is a rear elevation view thereof;

FIG. 7 is a right side view thereof, wherein the left side view is identical thereto;

FIG. 8 is a top view thereof, wherein the bottom view is identical thereto;

FIG. 9 is a front elevation view of a third embodiment of a sanitary pad showing the new design;

FIG. 10 is a rear elevation view thereof;

FIG. 11 is a right side view thereof, wherein the left side view is identical thereto; and,

FIG. 12 is a top view thereof, wherein the bottom view is identical thereto.

The even-length broken lines shown in the drawings illustrate portions of the sanitary pad that form no part of the claimed design.
